COMBINED RESONATOR AND NOZZLE FOR ACOUSTIC TREATMENT OF LIQUIDS

William K. Fortman, Syosset, N.Y., assignor to
Astrosonics, Inc., Syosset, N.Y.

Filed Aug. 28, 1962, Ser. No. 71,475

Term of patent 14 years

(Cl. D91—1)

FIG. 1 is a side elevation view of a combined resonator and nozzle for acoustic treatment of liquids showing my new design;

FIG. 2 is a plan view;

FIG. 3 is a bottom view;

FIG. 4 is a side elevation as viewed from the right side of FIG. 1; and

FIG. 5 is a side elevation viewed from the left side of FIG. 1.

I claim:

The ornamental design for a combined resonator and

nozzle for acoustic treatment of liquids, substantially as shown.
